UNITED STATES PATENT OFFICE

GEORGE ALBERT LYON, OF ALLENHURST, NEW JERSEY

MEANS FOR ORNAMENTING RIMS

Application filed July 11, 1930. Serial No. 467,325.

This invention relates to means for ornamenting the tire rims or wheel rims of automobiles.

It is common practice to plate with chromium or other plating material one of the side flanges of each rim. The plating material is applied only to the flange which occupies the outside position on the automobile. In the case of the so-called "Jackson" rim, in which one of the side flanges consists of a band or ring removably attached to the base of the rim, only this removable ring is plated.

The rims are made from hot rolled steel and the surfaces thereof are comparatively rough. The flanges are concavo-convex in cross section, the concave surface being on the outside of the flange. Because of the concave form of the surface to which the plating is applied, it is difficult to grind this surface and form-grinding wheels are required for this operation. In the application of the chromium plating to the side flange of a rim, the side flange is first copper plated, then buffed, after which a plating of nickel is applied. The surface is then again buffed and the chromium plating is applied over the coating of nickel. Because of the difficulty of grinding the surface of the steel and because of the number of operations required in plating the surface of the rim, the ornamentation of the rims in this manner adds considerably to the cost of the same. As such rims are now manufactured they rust quickly along the surface to which the plating is applied because of the abrasive action of dirt, stones and gravel thrown up by the tires.

The primary object of the present invention is to produce automobile rims which will have as attractive an appearance as rims which are plated in the manner above described, which may be manufactured at less expense than such rims and in which the ornamental surface thereof will not be subject to rust or corrosion.

With these and other objects in view, the invention comprises the novel and improved features, constructions and combinations of parts hereinafter described and particularly

pointed out in the claims, the advantages of which will be readily understood and appreciated by those skilled in the art.

The invention will be clearly understood from the accompanying drawings illustrating the invention in its preferred forms and the following detailed description of the constructions therein shown.

In the drawings:

Fig. 1 is a view in side elevation illustrating a construction embodying the invention applied to one form of rim;

Fig. 2 is a sectional view taken substantially on the line 2-2 of Fig. 1;

Fig. 3 is a detail view illustrating in cross section the removable ring of the rim shown in Figs. 1 and 2 at one stage in the process of manufacture;

Fig. 4 is a view corresponding to Fig. 3 illustrating the removable ring in its completed form;

Fig. 5 is a detail view similar to Fig. 4 illustrating a removable ring of slightly modified form;

Fig. 6 is a view in side elevation illustrating a construction embodying the invention applied to another form of rim;

Fig. 7 is a sectional view taken substantially on the line 7-7 of Fig. 6; and

Fig. 8 is a detail sectional view illustrating a portion of the rim with the invention applied thereto.

Figs. 1, 2 and 4 illustrate the invention as applied to a demountable rim of the type known as the "Jackson" rim. The demountable rim indicated as a whole at 2 is adapted to be mounted upon a wheel rim 4 and carries the tire indicated at 6. The demountable rim comprises a base 8 and side flanges 10 and 12 both of which are concavo-convex in cross section. The side flange 10 is formed integral with the base. The side flange 12 consists of a split ring mounted in a groove 14 in the base of the rim. This ring occupies the outside position when the demountable rim is applied to a wheel rim.

In order to impart an ornamental appearance to the outer face of this ring, an ornamental strip preferably of thin sheet metal having a highly polished outer surface is

mounted in a groove in said ring. As shown clearly in Fig. 4, the ring 12 is provided with a groove 16, the bottom surface 17 of which is concave corresponding with the cross-sectional form of the ring, and the groove is formed with side walls 18 which converge in a direction outwardly from the bottom wall of the groove. Within this groove is mounted an annular strip or ring 19 of thin flexible resilient sheet metal. The strip is made of a width somewhat greater than the minimum distance between the side walls 18 measured in a straight line, and is preferably formed with substantially a straight line cross section. Thus, the strip is preferably formed so that it conforms substantially to the surface of a cone.

In applying the ornamental strip 19 to the removable ring, one margin of the strip is inserted in the groove in the angle between one side wall and the base of the groove, the other margin of the strip being placed in contact with the outer face of the ring adjacent the other side wall of the groove. Pressure is then exerted upon the central portion of the strip to bend the same into concavo-convex form until the latter margin thereof clears the last mentioned side wall of the groove allowing the strip to be forced into the groove. This may be done progressively starting at one end of the ring and strip and working the strip progressively into the groove. Upon the release of the pressure upon the strip the resiliency of the metal will tend to cause the same to assume a substantially straight line cross section, thereby causing the edges of the strip to grip the side walls of the groove and hold the strip firmly in position therein.

The ornamental strip preferably consists of stainless steel or hard brass coated with nickel or chromium or of some other light metal which will not rust. The ornamental strip, however, may be made of ordinary steel plated with chromium or nickel or other suitable coating material. This strip is made of light gauge material, preferably about .012 to .025 of an inch in thickness, and is polished before being inserted in the groove in the removable ring.

In forming the removable ring 12, a strip of steel of the proper width is first rolled into the cross sectional form shown in Fig. 3 by a hot rolling operation. The groove 16 is also formed in a hot rolling operation. In forming the groove the side walls 18 are preferably formed so that they each extend at an angle slightly greater than a right angle to the bottom surface 17 of the groove. This will enable the roll by which the groove is formed to clear the side walls readily during the rolling operation. After the strip is given the shape shown in Fig. 3, and the groove is formed therein by hot rolling operations, the strip is rolled while cold into

the cross sectional shape shown in Fig. 4. This brings the side walls into positions in which they converge in a direction outwardly from the bottom wall of the groove so that the strip 19, when placed in the position shown in the groove, will be efficiently retained in place.

Fig. 5 shows a construction of the removable ring in which the side walls 18 of the groove respectively extend at an angle slightly less than a right angle to the bottom wall of the groove. The construction shown in Fig. 5 may be produced from a construction such as that shown in Fig. 4 by rolling the projections 20 at each side of the groove so as to deflect the side walls slightly inwardly toward the central portion of the groove.

In the construction shown in Figs. 6, 7 and 8, the invention is applied to the rim of a wire wheel for automobiles such as those used upon the Ford and Chevrolet. As shown in this figure the wheel comprises a hub 22, a rim 24 and a series of spokes 26 connecting the hub with the rim. The rim comprises a base indicated at 28 and side flanges 30 extending outwardly from the base. As shown clearly in Fig. 8, each side flange comprises a laterally and outwardly extending inclined portion 30 adjacent the base, a portion 32 extending laterally and inwardly at a slight angle toward the axis of the rim and an outer portion 34 extending laterally and outwardly from the portion 32. Thus each flange of the rim is formed with an annular recess indicated at 36.

In accordance with the present invention an annular ornamental strip 38, preferably of thin sheet metal, is applied to one of the side flanges of the rim so that it engages the side flange in the manner shown particularly in Fig. 7. This strip is preferably made of stainless steel, of light gauge, preferably about .015 to .035 of an inch in thickness. The strip is rolled into the form of a ring and into the concavo-convex cross sectional shape shown in Fig. 8 of the drawings and the ends of the ring are secured together. The ring is made of a size such that it may be fitted to the rim in substantially the manner shown in Figs. 7 and 8 and will hold itself in position through its own resilience. In the formation of the ring, the ring is constructed with an outside diameter slightly greater than the minimum inside diameter of the portion 32 of the rim. In applying the ring to the rim flange, the rim is forced into the recessed portion 36 of the flange so that the inner margin of the ring engages the portion 30 of the flange adjacent the base of the rim and so that the outer margin of the ring engages the portion 32 of the rim just within the line of its minimum inside diameter. When forced into this position the resilience of the metal will hold the ring securely in position. The ring is forced over tightly against the por-

tion 30 of the rim flange thereby bending back slightly the inner margin of the ring in the direction of the axis of the rim. The forcing of the ring into the portion 32 of the rim flange bends to a certain degree the outer margin of the ring inwardly toward the axis of the rim. The bending of the outer margin of the ring inwardly tends to deflect the inner margin laterally to the left, Fig. 8, and outwardly. Conversely, the bending back of the inner margin of the ring tends to force the outer margin of the ring outwardly. The pressure exerted by the inner margin of the ring upon the portion 30 of the rim flange and also the pressure exerted by the peripheral portion of the ring against the portion 32 of the rim flange resulting from the resilience of the material of the ring will form comparatively tight joints between the ring and the rim flange which will prevent the passage of water, sand and dirt between the ring and the rim flange.

The highly polished ring 38 imparts a highly ornamental and attractive appearance to the rim.

In the manufacture of the rings 38, the rings are formed from a strip of steel of sufficient length for the manufacture of a number of rings. This strip is rolled in a multiple rolling machine to give the same the proper cross sectional shape and to form the strip into a series of spirally arranged coils. The strip is then cut at the proper points to form the rings and the rings are either butt welded or overlapped and spot welded to form continuous rings. As above stated in the formation of the rings, each ring is so formed that its outer diameter is slightly larger than the minimum diameter of the portion 32 of the rim which it engages.

It is to be understood that the invention is not limited to the particular construction and arrangement of parts of the illustrated embodiments of the invention, but that the invention may be embodied in other forms within the scope of the claims.

Having explained the nature and object of the invention and having specifically described certain constructions embodying the invention in its preferred forms, what is claimed is:

1. An automobile wheel rim having a base and tire engaging side flanges extending outwardly therefrom and an ornamental ring strip of relatively thin sheet metal applied to the outer face of one of said flanges and interlocked with said flange to form an ornamental covering for at least a portion of said flange.

2. An automobile rim having a base and side flanges extending outwardly from said base and an ornamental resilient strip applied to one of said side flanges on the outside thereof and held in place by the resilient action of the material of the strip.

3. An automobile rim having a base and side flanges extending outwardly from said base and a cross-sectionally flexible and resilient strip applied to one of said side flanges and held in place by the resilient action of the material.

4. An automobile rim having a base and a side flange having an annular recess and an ornamental ring, forced into said recess and held therein by the resilience of the ring.

5. An annular transversely flexible and resilient ornamental strip for automobile rims adapted to be applied to one of the side flanges of a rim and constructed to hold itself in place by the resilient action of the material.

6. An ornamental annular strip for automobile rims having a concavo-convex form in cross section and constructed and arranged to be applied to one of the side flanges of a rim and to hold itself in position by the resilient action of the material of said strip.

7. An ornamental rim having a base and tire engaging side flanges extending outwardly from said base and an annular ornamental strip of sheet metal applied to the outer face of one of said flanges in concentric relation to the rim and held yieldingly in position solely by its interconnection with said outer face of the flange.

8. An automobile rim having a base and side flanges extending outwardly from said base, one of said flanges having a groove formed with converging side walls and a flexible resilient ornamental strip mounted in said groove and held in place by the cross sectional resilience of the material.

9. An automobile rim having a base and side flanges extending outwardly from said base for engaging the tire to hold the same on the rim, one of said flanges having an annular recess and an annular shoulder and an annular strip of relatively thin sheet metal constructed to be applied to the outer face of one of said flanges and to extend into said recess and having an outer margin arranged to be expanded into contact with said shoulder to hold the strip in said groove.

10. The combination with a wheel rim of an ornamental split bead therefor held in cooperation with the rim by the inherent resiliency of the bead.

11. The combination with a wheel rim of an ornamental bead therefor of curved transverse cross section and held in tight cooperation with the rim solely by its engagement with the rim.

Signed at New York, New York, this 24th day of June, 1930.
